UNITED STATES PATENT OFFICE

DONALD R. WILSON, OF PESHASTIN, WASHINGTON

NAIL TONGS

Application filed November 25, 1929. Serial No. 409,686.

The present invention relates to an improved article handling device and the primary object of the invention is to provide a tool or device of this character adapted to facilitate the handling of nails, staples, tacks, etc., without injury to the hand of a person handling the articles. A further object of the invention is to provide an improved construction for nail tongs which will permit ready and easy removal of nails and the like from kegs, bins and other containers and which device may be operated by one hand, thus leaving the other hand of the operator free to hold a receptacle for receiving the nails removed by the tongs.

A further object resides in the arrangement whereby the companion pair of pivotally connected members are normally urged to a spread position, with means for limiting the spreading movement of the members beyond a point permitting ready grasping of the handle portions by one hand of the operator.

A further object of the invention is to provide a device of this character which may be very economically constructed from a suitable gauge of bar metal and one wherein the nail engaging portions are of such formation as to permit ready and easy grasping of the nails to be handled.

Other objects and advantages of the invention will be apparent during the course of the following detailed description, taken in connection with the accompanying drawing forming a part of this specification and in which drawing:

Figure 1 is a perspective view of the improved tongs shown in their normal spread position.

Figure 2 is a side elevation showing the tongs contracted.

Figure 3 is an enlarged transverse section thru the tongs on line 3—3 of Figure 1.

In the drawing, and wherein similar reference characters designate corresponding parts, the improved tongs include a pair of lever members 5 and 6 pivotally connected intermediate their ends by means of a hinge member 7, the lever members 5 and 6 being normally spring urged to a spread position by the spring means 8. The lever members

5 and 6 are of substantially like formation and may be constructed from a suitable gauge of metal rod preferably of cylindrical formation.

The member 5 is formed with a bail-like hand grip or handle portion forming parallel side arms 10 connected at their upper ends by the cross piece 11. The lower end of each side arm 10 is coiled or looped into a closed eye 12. These coils or eyes 12 are disposed in axial alignment to one side of the major plane of the handle portion. From the coils or eyes 12 the bar is extended to provide a claw portion embodying arms 14 extending in substantial alignment with the respective side arms 10. Each arm 14 adjacent its lower end is bowed outwardly and then inwardly providing a hooked portion 15 at the lower end of each arm 14.

The companion lever member 6 is formed with a bail-like hand grip or handle portion embodying parallel side arms 20 connected at their upper ends by a cross piece 21. Formed at the lower end of each side arm 20 is a loop or coil providing closed eyes 22 which are disposed inwardly of the eyes 12 in axial alignment therewith. From the coils or eyes 22 the bar is extended providing arms 24 which extend in substantial alignment with their companion arms 20. These arms 24 as will be observed have a very slight outward bow and at their lower ends are inturned to form hooked portions 25 which are directed toward the hook portions 15.

The coils 12 and 22 of the members 5 and 6 respectively are oppositely coiled which causes the arms of the claw portions to cross one another as clearly shown in Figure 2, while the side arms of the handle portions are not crossed and extend upwardly at the outer sides of the coils.

The hinge member 7 is in the form of a hinge pin having its cylindrical shank portion 26 extended thru the eyes 12 and 22. One end of the shank 26 is provided with an enlargement or head 27 for engaging one of the eyes 12, while the opposite end of the shank portion is looped about the convolution of the companion eye 12 and ex-

tended inwardly between the companion arms 14 and 24 providing a stop 28 for limiting spreading movement of the lever members. As will be observed in Figures 1 and 5 2 the stop 28 projects inwardly between the companion arms 14 and 24 above the point at which the arms cross. This looped end 10 of the hinge pin about the eye 12 co-acts with the head 27 for preventing longitudinal shifting of the hinge member in either direction.

The spring means 8 is in the form of a coil 15 spring encircling the shank 26 between the eyes 22, with one end of the coil spring extended downwardly and hooked about one of the arms 24 as at 32, and with the opposite end of the spring extended downwardly and looped about an arm 14 of the companion lever member as at 34. The action of the spring 8 is to normally urge the claw portions of the device 20 to a spread position limited by means of the stop 28. This limited spreading movement of the lever members also prevents spreading of the handle portions beyond an extent permitting an operator to readily grasp the hand portions with one hand for closing of the tongs. In the dotted line 25 showing of the tongs in Figure 2 is shown the manner in which the lever members 5 and 6 are spread by the spring 8 and limited in their spreading movement by the stop 28 extended between one pair of crossed arms 14 and 24.

30 By so having the arms 24 of the one lever member 6 bowed to a very slight extent permits of the arms 24 being more easily forced into the nails to be handled. It will be noted that the device is constructed of but four separate pieces.

40 From the foregoing description it will be apparent that a novel and improved construction for nail tongs has been provided embodying a novel arrangement whereby the 45 tongs are normally held open for ready gripping action upon the nails. It will also be apparent that a novel arrangement has been provided wherein the operator need use but one hand in removing nails and the like from suitable containers and which device operates automatically for dropping these nails upon release of the operator's grip upon the handle portions of the device.

50 Changes in detail may be made to the form 55 of invention herein shown and described, without departing from the spirit of the invention or the scope of the following claims.

I claim:

55 1. A device of the class described comprising a pair of U-shaped lever members, a hinge member pivotally connecting the lever members intermediate their ends to provide a pair of co-acting handle portions and a pair of 60 co-acting claw portions arranged respectively

above and below the hinge member, spring means normally urging the lever members to a spread position, and a stop extension formed on one end of hinge member and engageable by the claw portions for limiting spreading movement of the lever members. 70

2. A device of the class described comprising a pair of U-shaped lever members each provided with side arms, said side arms of each lever member each being coiled intermediate its ends providing closed hinge eyes, a hinge pin extending thru the eyes for pivotally connecting the lever members intermediate their ends and providing handle portions above the eyes and claw portions below the eyes, said arms of the claw portions of the levers being crossed in spaced relation below the hinge eyes, spring means normally urging the lever members to a spread position, and a stop extension at one end of the hinge pin and bent inwardly above the crossing point of the claw arms for limiting spreading movement of the lever members. 80

3. A device of the class described comprising a pair of lever members each of one piece construction and each formed with a bail-like handle portion and bowed claw portions connected by a loop with the handle portions, a hinge pin extended thru the loops pivotally connecting the lever members with the bowed claw portions thereof in crossed relation, a coil spring disposed about the hinge pin and having the ends thereof engageable one with each lever member for normally urging the lever members to a spread position, and a stop extension formed at one end of the hinge pin to extend between one pair of co-acting claw portions for limiting spreading movement of the lever members. 90

4. A device of the class described comprising a pair of lever members each including a handle portion embodying side arms and bowed claw arms joined by a loop with the lower ends of the side arms, a hinge pin extending thru the loops for pivotally connecting the lever members with the claw arms crossed at a location spaced below the loops, said pin having a head formed at one end and having its opposite end looped and extended between one pair of co-acting claw arms above the crossing point of the arms, and a coil spring encircling the hinge pin and connected with the claw arms for normally urging the lever members to a spread position. 100

5. A device of the class described comprising a pair of U-shaped lever members each embodying a pair of side arms coiled into an eye intermediate their ends to form handle portions and claw arms, a hinge pin extending thru the eyes for pivotally connecting the members, means normally urging the lever members to a spread position, and stop means provided on the hinge pin for limit- 110 115 120 125 130

ing spreading movement of the lever members, said claw arms of one lever member having a substantial outward bow therein terminating in a hook at the lower ends of the arms and the claw arms of the companion lever member having a very slight outward bow and terminating in slightly inwardly turned hooks at their lower ends.
